UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

1,301,705.

Specification of Letters Patent. Patented Apr. 22, 1919.

Application filed August 9, 1918. Serial No. 249,092.

To all whom it may concern:

Be it known that I, OSCAR JUNGGREN, a citizen of the United States, residing at Schenectady, in the county of Schenectady, State of New York, have invented certain new and useful Improvements in Elastic-Fluid Turbines, of which the following is a specification.

The present invention relates to elastic fluid turbines and especially to the blading for such turbines. Particularly in the lower pressure stages of elastic fluid turbines the blades become of considerable length and where they are supported only at the base and tip there is always danger of their being set into vibration which may ultimately cause them to break. It is accordingly desirable to provide some means for preventing such vibrations and the object of my invention is to provide an improved arrangement of vibration means comprising projections between adjacent buckets, and an improved method of positioning such projections.

For a consideration of what I believe to be novel and my invention, attention is directed to the accompanying description and the claims appended thereto.

In the drawing, Figure 1 is a side elevation partly in section of a portion of a bucket wheel embodying my invention, and Fig. 2 is a top plan view, partly in section.

Referring to the drawing, 5 indicates a portion of the rim of a turbine wheel or disk and 6 turbine buckets or blades mounted thereon, the outer ends of the blades being connected by a bucket cover 7. This may be taken as typical of any turbine wheel structure. Now according to my invention, I provide preferably on the back of each bucket and at or about its central portion, a projection 8 which extends the full width of the bucket and in the completed wheel engages the adjacent surface of the next bucket. These projections 8 may be formed as integral parts of the buckets or they may be separate pieces of material connected to the buckets by brazing, welding or other suitable means. In any event they are made comparatively light and extend at least originally at an angle other than a right angle to the buckets so that they may be bent into engagement with the adjacent bucket. They are also preferably provided with

holes 9 to make them light in weight and provide means so the projections can be expanded by means of a suitable tool to bring them into firm engagement with the next adjacent bucket.

In constructing a turbine wheel embodying my invention, the projections 8 are attached to the buckets, or the buckets are formed with such projections as the case may be, and the projections are set at such an angle to the buckets and are of such length that they extend outward a distance less than the width of the space between two adjacent buckets. The buckets are then assembled on the rim of the wheel and the bucket cover put into place. Since the projections 8 extend outward a distance less than the width of the space between adjacent buckets they will in no way interfere with the buckets taking any position they want to. In other words the buckets can assume their natural positions. After the buckets are assembled on the wheel and the bucket cover is in place, the projection 8 on each bucket is then bent into engagement with the next adjacent bucket, for example, by tapping it with a suitable tool. This then forms a complete ring supporting the centers of the buckets. If found desirable the projections may be expanded over a part or all of their width by tapping a taper plug 88 into the holes 9. This insures contact of the free ends of the projections throughout their widths with the next adjacent bucket surfaces.

My invention, it will be seen from the foregoing, provides a simple and easily carried out method of providing projections between adjacent buckets whereby the projections may be made the full width of the buckets and even contact of them throughout their width with the buckets insured. Since the projections may be provided on the buckets, as by fastening them to the buckets, before the buckets are assembled on the wheel the result is a simple, cheap and easily performed operation. When being assembled the buckets can assume their natural positions. The bending and expanding of the projections into engagement with the next adjacent buckets is a simple and easily performed operation and one not likely to put any strain on the buckets, or in any way derange them.

What I claim as new and desire to secure by Letters Patent of the United States, is:—

1. The improved method of constructing a turbine wheel with braces between the buckets, which comprises providing projections on the buckets which extend at an angle other than a right angle thereto and outwardly a distance less than the width of the space between adjacent buckets, assembling the buckets on the wheel rim, and then bending the projection on each bucket so that it engages the next adjacent bucket.
2. The improved method of constructing a turbine wheel with braces between the buckets, which comprises providing projections on the buckets, which are of less length than the space between the buckets, assembling the buckets into place on the wheel rim, and then expanding said projections so that each engages the next adjacent bucket.
3. The improved method of constructing a turbine wheel with braces between the buckets, which comprises providing projections on the buckets which extend at an angle other than a right angle thereto and outwardly a distance less than the width of the space between adjacent buckets, assembling the buckets on the wheel rim, and then bending the projection on each bucket and expanding it so that it engages the next adjacent bucket.
4. The combination with a bucket wheel of projections of comparatively thin material attached to an intermediate part of the buckets so as to project at angles other than a right angle therefrom whereby such pro-

jections may be bent to bring their free ends into engagement with the next adjacent buckets.

5. The combination with a bucket wheel having comparatively long buckets thereon of projections attached to the backs of at least some of the buckets, said projections being formed of bendable material and extending at angles other than a right angle to said buckets whereby the free ends of said projections may be bent up into engagement with the faces of the next adjacent buckets.

6. The combination with a bucket wheel having comparatively long buckets thereon of a projection attached to one side of a bucket and extending at an angle other than a right angle toward the next adjacent bucket, said projection being of substantially the full width of the bucket and adapted to be bent into engagement with such next adjacent bucket.

7. A bucket for a turbine having a bendable projection thereon located approximately midway between its ends and extending at an angle other than a right angle thereto.

8. A bucket for a turbine having a bendable projection thereon located approximately midway between its ends and extending at an angle other than a right angle thereto, said projection being provided with one or more holes.

In witness whereof, I have hereunto set my hand this 7th day of August 1918.

OSCAR JUNGGREN.
